CLAIM

The ornamental design for the articulated communication device with a port connection, as shown and described.

DESCRIPTION

FIG. 1 is a perspective view of my design for an articulated communication device with a port connection, shown in the articulated position; the device will bend from the shown ninety degree angle to a one-hundred and eighty degree angle or straight line.

FIG. 2 is a top view thereof.

FIG. 3 is a front elevational view thereof.

FIG. 4 is a left side elevational view thereof; the right side is symmetrical.

FIG. 5 is a rear elevation view thereof; and,

FIG. 6 is a bottom view thereof.
